(57) **CLAIM**

The ornamental design for an amplifier housing, as shown and described.

DESCRIPTION

FIG. 1 is a perspective view of a new design for an amplifier housing.

FIG. 2 is a top plan view of the new design of FIG. 1.

FIG. 3 is a right elevational view of the new design of FIG. 1.

FIG. 4 is a front elevational view of the new design of FIG. 1; and,

FIG. 5 is a bottom plan view of the new design of FIG. 1. The broken lines illustrated in the figures are not part of the design sought to be patented and are shown to illustrate the environment related to the claimed design. The broken lines that define the bounds of the claimed design form no part thereof.
